UNITED STATES PATENT OFFICE.

ORLANDO P. HARGROVE, OF WAYLAND, NEW YORK.

BUMPER FOR LOOMS.

Application filed January 11, 1924. Serial No. 685,753.

To all whom it may concern:

Be it known that I, ORLANDO P. HARGROVE, a citizen of the United States, residing at Wayland, in the county of Steuben 5 and State of New York, have invented a new and useful Improvement in Bumpers for Looms, of which the following is a specification.

This invention relates to improvements in 10 bumpers of the kind with which the picker stick of a loom is adapted to cooperate to stop the movement of the picker stick.

The objects of this invention are to provide a bumper of this kind which is simple 15 in construction and effective in operation and on which the leather strip, with which the picker stick impacts, is so mounted that it may be readily removed and replaced by another leather strip; also to provide a bumper of this kind which offers a gradually 20 increasing resistance to the movement of the stick and which can be readily adjusted to adapt a bumper to offer an increased or decreased resistance to the movement 25 of the stick, as may be desired; also to provide a bumper of this kind which is of strong and durable construction and which is economical in the use of leather strips; also to improve the construction of 30 bumpers of this kind in other respects hereinafter specified.

In the accompanying drawings:

Fig. 1 is a side view of a bumper embodying my invention, showing the same mounted on the frame of a loom and showing the picker stick of the loom striking the bumper.

Fig. 2 is a top plan view of the bumper, on an enlarged scale.

Fig. 3 is a top plan view thereof showing some of the parts of the bumper in different positions.

Fig. 4 is a side elevation thereof.

Fig. 5 is a sectional elevation thereof on line 5—5, Fig. 2.

Fig. 6 is a rear elevation thereof.

Fig. 7 is a fragmentary top plan view of a bumper of slightly modified construction.

A, Fig. 1, represents a part of the frame of a loom and B a picker stick which is pivoted at its lower end to the loom and which is movable about its pivot to strike the shuttle for the purpose of passing the same across the loom. A bumper embodying my invention is mounted on the part A 50 of the frame of the loom and the picker

stick B is shown in engagement with the bumper.

The bumper shown in the drawings and which embodies my invention includes a substantially C-shaped frame member C 60 which has a base or body portion *c* provided with suitable means for securing the same to the frame of a loom, such for example, as holes *c'* through which bolts or other securing means (not shown) may pass, 65 which secure the frame of the bumper to the frame of the loom. The frame C of the bumper has a pair of arms *c*² which extend forwardly from the body portion and which preferably form stop shoulders *c*³ 70 with the body portion *c* of the bumper frame.

Each of the forwardly extending arms *c*² of the frame of the bumper has pivotally secured thereon a lever D. In the construction shown for this purpose, each of 75 the arms is provided with an aperture through which a pivot pin *d* extends and the lever D is provided with a corresponding aperture for the pivot pin *d*, which may be secured in place in any suitable or desired manner. The lever D and the forwardly extending arms *c*² may be of any suitable or desired construction, the arms shown being flattened on their upper faces and the levers D being of a shape corresponding to the shape of the forwardly extending arms so that the flat faces of the levers rest against the flat faces of the arms. The rear end *d'* of each of the levers is adapted to engage with the shoulders *c*³ on 80 the frame member of the bumper to limit the extent to which the levers D may swing relatively to the frame member of the bumper.

A strap F of leather or other flexible material is stretched across the outer ends of the two levers and for this purpose the outer ends of each of the levers D is provided with means for attaching the strap thereto. In the construction shown each of the levers 100 has an upwardly extending post or arm E, to which the end of a strap F may be secured. These upwardly extending arms or posts of the levers are preferably substantially L-shaped in cross section so as to resist the strain due to the striking of the picker stick against the leather strap F and are preferably provided with rounded shoulders or edges *e* around which the ends of the strap pass. The strap is secured to 105 110

the sides of the posts in any suitable manner, for example, by means of bolts f which pass through holes in the posts E and in the leather strap F and which engage clamping pieces or washers f' to press the ends of the strap against the posts E to securely hold the ends of the strap of the posts.

The swinging of the levers D from the position shown in Fig. 2 to that shown in Fig. 3, due to the picker stick B striking against the strap F , is opposed by suitable resisting means, which also tend to keep the strap taut across the space between outer ends of the levers. In the construction shown this is accomplished by means of one or more springs G which connect the inner ends of the levers D . The springs shown are connected with the levers D by means of pins or posts g secured to the levers in rear of the pivot pins d and extending upwardly therefrom, and means of any suitable kind may be provided for securing the springs on the posts. In the construction shown, each of the springs is provided at its ends with eyes into which the posts g are adapted to extend, and nuts or the like g' are provided which engage with threaded parts on the posts for holding the eyes of the springs on the posts. If desired, spacing sleeves g^2 may be provided for holding the springs in definite relation to the posts. These springs, therefore, may be easily disconnected from the levers D and may be replaced by springs of different strength if desired, or by other springs, in case of damage. As shown in Fig. 2, the spring normally pulls the levers D into a position in which the shoulders d' thereof engage the shoulders c^3 of the frame member of the bumper. Consequently the strap F will not become unduly stretched due to a continual pull thereon by the spring, thus prolonging the life of the strap. By changing the springs and replacing them by stronger or weaker springs, the bumper can readily be adapted to cooperate with different picker sticks in such a way as to properly cushion the blows of the sticks.

Fig. 7 shows a bumper of slightly modified construction which is so made that the fulcrum of each of the two levers may be changed as may be desired, for the purpose of further increasing the range of cushioning effects which may be produced. In this case the levers D' and the arms of the frame of the bumper are provided with two or more holes, into either of which a pivot pin I may be inserted. In the construction shown, the pivot pin I is shown in one of the holes, and K represents the other hole. When the parts are in the position shown in Fig. 7 the spring will exert a considerably greater pull upon the strap than when the pivot pin I is in the hole K . Consequently by proper arrangement of the pivot

pin, as well as by selection of springs of different strengths, the resistance of the strap to the movement of the picker stick can be varied as may be desired for the particular picker stick with which the bumper is to cooperate.

The bumper described is strong and rugged in its construction and is economical in that it uses a comparatively short leather strap F , and since these straps must be of a high grade of leather and are quite expensive, this item is of considerable importance. The strap can be easily mounted on the levers or removed therefrom, without removing the springs G , since when the strap is removed, the spring merely holds the rear ends of the levers D against the shoulders c^3 . By providing the arms c^2 and the levers D with extensive flat bearing surfaces, the bumper is well able to resist severe blows to which it is subjected by the picker sticks. By means of the construction shown, a blow of the picker stick against the strap F will result in a swinging of both of the levers about their pivots so that there is no grinding or rubbing action of the picker stick against the strap F , which helps to increase the life of the strap.

I claim as my invention:

1. A bumper for the picker stick of a loom or the like, including a rigid structure, having spaced forwardly extending arms, levers pivotally mounted on the arms, a flexible strap fixedly attached at its ends to the levers, and a spring connecting the levers for holding the strap normally taut and to maintain the levers normally within the bounds of the structure.

2. A bumper for the picker stick of a loom or the like, including a frame having a pair of spaced arms extending therefrom, levers pivotally mounted on the respective arms, a strap constituting the sole connection between the levers at one end, said strap being fixedly secured at its ends to the levers, and a spring constituting the sole connection between the other ends of the levers and normally holding the strap taut and the levers within the bounds of the frame and the arms.

3. A bumper for the picker stick of a loom or the like, including a frame having a pair of arms extending therefrom, there being abutment shoulders on the frame at the inner ends of the arms, levers fulcrumed upon the respective arms, a flexible strap fixedly secured at its ends to the respective levers and constituting the sole connection between said levers at one end, and a spring connected to the end portions of the levers for holding said levers normally pressed against the shoulders and the strap normally taut.

ORLANDO P. HARGROVE.
